COLLAR SUPPORT

John A. Fine, Sr., Knoxville, Tenn.

Application November 5, 1946, Serial No. 707,948

2 Claims. (Cl. 223—83)

1

This invention relates to collar supports for laundered and new shirts.

It is an object of the present invention to provide a collar support wherein the collar band on the shirt will be supported both upon the inner side and upon the outer side thereof whereby to give a more solid bracing of the collar neck band at the front faces of the collar so as to prevent the tabs end from being turned up as when a load is placed on the shirt.

It is another object of the present invention to provide a collar support which can be easily constructed and wherein there is provision made upon the support after portions have been disposed on the inner side and on the outer side of the band, for a locking device adapted to be extended forwardly and have its wing portions extend over the front faces of the tabs.

It is another object of the present invention to provide a collar support wherein the portion that connects the support portions together need only to be bent throughout a small distance in order to fit the collar support into the collar and whereby the collar support can be inserted within the collar without any great degree of bending of the material being required.

It is another object of the present invention to provide in a collar support of a type adapted to provide double bracing of the neck band at the inner and outer sides thereof wherein there will be provided means on the support which will be adapted to be extended along the top of the collar and at the front thereof whereby to protect the top end of the collar from becoming soiled as the shirts are stacked one upon the other.

It is still another object of the present invention to provide in a collar support of the double bracing type, means adapted to unite with the front of the shirt to keep the collar support from slipping from side to side.

For other objects and for a better understanding of the invention, reference may be had to the following detailed description taken in connection with the accompanying drawing in which:

Figure 1 is a fragmentary front face view of a shirt folded up to receive the collar support and with the collar support of one form of the invention disposed in place upon opposite sides of the neck band.

Figure 2 is a cross-sectional view taken on line 2—2 of Figure 1 and looking in the direction of the arrows thereof.

Figure 3 is a front view of the collar support removed from the shirt and bent along the narrow connection part of the portions extending

along the inner and outer sides of the neck band.

Figure 4 is a plan view of the collar support before it has been folded and showing the laterally extending slots and the narrow neck portion 5 along which the fold is made.

Figure 5 is a plan view of the top of a folded shirt with a collar support of modified form, wherein there is means provided on the top of the folded portion which is adapted to extend over the top edge of the collar adjacent the tab ends of the same.

Figure 6 is a cross sectional view taken on line 6—6 of Figure 5 and looking in the direction of the arrows thereof.

Figure 7 is a front view of the collar support according to the form of the invention shown in Figure 5 after it has been folded along its intermediate portion of the same removed from the shirt.

Figure 8 is a plan view of the collar support in its unfolded state to show the shape of the various portions of the same.

Referring now particularly to Figures 1 to 4, 10 represents a shirt which has been folded after 25 having been made or after having been laundered and so as to have the collar presented to the top of the folded shirt. The shirt has the usual collar 11 thereon and a neck band 12. A paper band 13 serves to hold the folded shirt together.

As shown in Figure 4 the collar support according to this form of the invention is provided with two portions 14 and 15 adapted when folded about a small connecting portion 16 to lie respectively against the inner side and outer side faces of 35 the neck band whereby to provide a double bracing of the neck band so as to prevent any crushing of the neck band and any bending of the collar tabs as would be effected if the neck band were actually crushed. The tabs of the collar 11 are indicated at 17 and 18.

The ends of the neck band 12 are retained together by a button 21 Figure 2. The collar support after having been formed as shown in Figure 4 and at the time when it is desired to insert

45 the same within the collar 11 is folded along its connecting portions 16 so that the portions 14 will lie in rear of portion 15. The collar support is then inserted about the collar neck band so that the portion 14 will lie on the inner side of the same and the portion 15 will extend from the center of the support to locations beneath the collar 11 and parallel to the portion 14 on the inner side of the neck band. Thus a double bracing of the collar neck band is had.

50 The connecting portion 16 has below it a tri-

angular shaped portion 22 adapted to have its ends disposed over the top faces of the tabs 17 and 18 whereby to prevent any lateral slippage of the collar support within the collar. Each of the portions 14 and 15 comprise two wings extending respectively from the opposite sides of the connecting portion 16. Little effort is required to effect the folding of the portions about the connecting portions 16 as would be the case if the entire part of the support were to be folded. After this folding has been effected the wings are inserted into place with the wings of the portion 15 lying on the outer side of the neck band and under the collar. The portions are thereupon given a rounded shape so that the upper edges will lie parallel and be raised to the same extent.

Referring now to Figures 5 to 8, there is shown a modified form of my invention. According to this form of the invention, there is provided a body of sheet material of elongated, generally rectangular shape providing two elongated strips 25 and 26 adapted to lie respectively on the inner side and outer side of the neck band. At the center there is provided a connecting portion 27 adapted to connect the two portions 25 and 26 together. At each opposite side of this connecting portion 27 there is an elongated, U-shaped cut, these U-shaped cuts providing two oppositely-extending, elongated tabs 28 and 29 lying respectively upon opposite sides of the portion 27. Medial cuts extend from the outer ends of the U-shaped cuts to the opposite ends of the body to render the body longitudinally foldable. The collar support is folded at opposite ends of the connecting portion 27 and then one of the portions 25 or 26 is slid into the collar at opposite sides of the connecting portion 27 and the portions 25 and 26 lie respectively upon opposite inner and outer faces of the neck band. With this support, like with the previously described support, a double bracing of the neck band is provided. The tabs 28 and 29 will lie over the top of the collar at opposite sides of the portion 27 so as to provide along with the portion 27 means for preventing the front top portion of the collar from becoming soiled when the various shirts are stacked upon one another. In order to prevent the support from sliding or slipping or pivoting out of the collar there is provided upon each of the portions 25 and 26, notches 31 and 32 respectively. The end portions of these notches as indicated at 33 will catch upon the shirt material such as upon the seams of the shirt front and the support will thereby be prevented from pivoting or tilting out of its position beneath the collar and about the neck band.

While changes may be made in the detailed construction, it shall be understood that such

changes shall be within the spirit and scope of the present invention as defined by the appended claims.

What is claimed is:

- 5 1. In a collar support, inner and outer collar supporting members formed of sheet material and separated from each other along adjacent edges, a medial connecting portion formed in one integral piece with said members and joining said members together, and tabs extending in opposite directions from said medial connecting portion and integral therewith, said tabs being symmetrically arranged on opposite sides of the adjacent edges of said members in positions to overlie the upper edge of the collar enclosed by said members and normal to the members in upstanding relation, said tabs being elongated in longitudinal alignment and approximately of uniform width throughout the major portion of 10 the length thereof, and said tabs being symmetrical about the minor axis of said medial portion.
- 15 2. In a collar support, inner and outer collar supporting members formed of sheet material and separated from each other along adjacent edges, a medial connecting portion formed in one integral piece with said members and joining said members together, and tabs extending in opposite directions from said medial connecting portion and integral therewith, said tabs being symmetrically arranged on opposite sides of the adjacent edges of said members in positions to overlie the upper edge of the collar enclosed by said members and normal to the members in upstanding relation, said tabs being elongated in longitudinal alignment and approximately of uniform width throughout the major portion of 20 the length thereof, and said tabs being symmetrical about the minor axis of said medial portion.
- 25 3. In a collar support, inner and outer collar supporting members formed of sheet material and separated from each other along adjacent edges, a medial connecting portion formed in one integral piece with said members and joining said members together, and tabs extending in opposite directions from said medial connecting portion and integral therewith, said tabs being symmetrically arranged on opposite sides of the adjacent edges of said members in positions to overlie the upper edge of the collar enclosed by said members and normal to the members in upstanding relation, said tabs being elongated in longitudinal alignment and approximately of uniform width throughout the major portion of 30 the length thereof, said members and tabs being stamped from thin sheet material in one integral piece initially flat and foldable to collar supporting positions, and said tabs being symmetrical about the fold line of said members.
